DECORATIVE PANEL FOR CIGARETTE LIGHTERS OR THE LIKE

Stanley Bowden, Brooklyn, N.Y., assignor to Rogers Inc.,
New York, N.Y., a corporation of New York

Application March 16, 1959, Serial No. 55,009

Term of patent 14 years

(Cl. D48—27)

Figure 1 is a view in side elevation of a decorative panel for cigarette lighters, showing my new design, the broken lines are for illustrative purposes only, and

I claim:

The ornamental design for a decorative panel for cigarette lighters or the like, as shown and described.
